WORK FEEDING AND POSITIONING
MECHANISMEden T. Kitchell, Dallas, Tex., assignor to
J. E. Bush, Dallas, Tex.

Application February 14, 1947, Serial No. 728,575

2 Claims. (Cl. 198—160)

1

This invention relates to new and useful improvements in work feeding and positioning mechanisms.

One object of the invention is to provide an improved mechanism for continually feeding work in sequence and maintaining the same in a fixed position during a desired operation so as to reduce manual handling of the work to a minimum and thereby simplify and speed the performance of said operation.

An important object of the invention is to provide an improved work feeding and positioning mechanism adapted to intermittently feed work to a machine for a desired operation, the feeding being suspended during such operation and being resumed at will upon the completion of said operation.

A particular object of the invention is to provide an improved mechanism, of the character described, having a conveyor for feeding work to a machine with means overlying and co-acting with the conveyor for maintaining work in engagement therewith to facilitate feeding of the work and to hold the same stationary during the operation of the machine.

Another object of the invention is to provide an improved mechanism, of the character described, wherein the conveyor is adapted to be actuated intermittently for alternately feeding and maintaining work stationary to permit semi-automatic manipulation of the work in performing a desired operation.

A construction designed to carry out the invention will be hereinafter described together with other features of the invention.

The invention will be more readily understood from a reading of the following specification and by reference to the accompanying drawing, wherein an example of the invention is shown, and wherein:

Fig. 1 is a side elevational view of a work feeding and positioning mechanism, constructed in accordance with the invention, and shown associated with a riveting machine.

Fig. 2 is a plan view of the mechanism and a portion of the machine.

Fig. 3 is a transverse, vertical, sectional view, taken on the line 3—3 of Fig. 1.

Fig. 4 is a transverse, vertical, sectional view, taken on the line 4—4 of Fig. 1, and

Fig. 5 is a vertical, sectional view, taken on the line 5—5 of Fig. 4.

In the drawings, the numeral 10 designates a support or table having the usual uprights or legs 11 and longitudinal angle bars or flanged side rails 12 which are connected in parallel relation by similar transverse end bars 13 and intermediate cross bars 14. As will be hereinafter more fully explained, one or more supports or tables 10 are adapted to be employed in con-

2

junction with a machine, such as an automatic riveting machine 15, for supporting work as it is fed to and from the machine (Figs. 1 and 2). The later is of conventional construction and includes a pedestal 16 upon which is mounted a reciprocating ram or plunger 17 adapted to coact with an anvil block 18 projecting laterally from the pedestal beneath the plunger. Coacting dies 19 and 20 are mounted on the plunger 17 and anvil block 18, respectively, and suitable rivets (not shown) are fed to the lower die 20 by a curved track 21. As is most clearly shown in Figs. 2 and 5, the anvil block 18 is fastened by suitable bolts 22 to the adjacent end bars 13 of the tables which preferably are disposed in alignment on either side of the machine 15.

Work, such as metallic louvers L and end brackets B (Figs. 1 and 3), is adapted to be supported by the tables to facilitate riveting of the same by the machine 15. A plurality of louvers L are adapted to be riveted to each bracket B which extends longitudinally of the tables, while said louvers depend substantially vertically therefrom. For feeding the work to the machine, an endless chain conveyor 23 extends longitudinally of the right-hand table 10 adjacent its forward margin or side rail 12 and passes over end sprockets 24 and 25 which are supported by rotatable shafts 26 and 27, respectively. Idler sprockets 28, carried by shafts 29, are disposed intermediate the end sprockets 24 and 25 for supporting the upper flight of the conveyor chain 23. The shafts 29 extend transversely of the table 35 below the side rails and are journaled in yokes or U-shaped brackets 34 which are welded, or otherwise secured, to and depend from said rails in spaced relation. A longitudinal angle bar or rail 31 is secured to the underside of the forward 40 side rail and projects forwardly thereof between the sprockets 24 and 25 to provide a guide for the upper flight of the endless chain (Figs. 1, 3 and 4). The flanges of the guide rail 31 are directed forwardly and upwardly and the chain 45 rides upon the upwardly-directed flange. Cut-out portions or recesses 32 are formed in the latter for accommodating the idler sprockets 28. A suitable chain guard 33 for the lower flight of the endless chain is carried by the forward legs 50 of the brackets 34.

Similar yokes or brackets 34 and 35 support the shafts 26 and 27, respectively, of the end sprockets 24 and 25. In order to permit tightening of the chain 23, the bracket 34 is adjustably 55 mounted by being suspended from a frame 36 which is slidably supported upon and between the side rails of the table. Suitable bolts 37 extend through elongated openings or slots 38 formed in the frame 36 and are screw-threaded into the side 60 rails for fastening said frame and its bracket in adjusted positions. The frame has a transverse

angle bar 39 at its inner end for supporting suitable screws 40 which bear against one of the cross bars 14 of the table for varying the position of said frame. Manifestly, tightening of the chain may be accomplished by inward rotation of the screws 40 so as to slide the frame outwardly toward the end of the table, while retracting of said screws permits inward movement of said frame so as to loosen said chain. Suitable straps 41 connect the end bar 39 of the frame to the 10 lower portion of the bracket 34.

As is most clearly shown in Figs. 2 and 4, the sprocket 25 has the rear or inner end portion of its shaft 27 terminating short of the rear leg of the bracket 35 and journaled in a substantially upright arm 42 secured to and projecting upwardly from the lower portion of said bracket. The rear extremity of the shaft is polygonal or angular in cross-section to provide wrench faces 43 for engagement by a ratchet lever 44 which is held in engagement therewith by a suitable screw 45. The ratchet lever 44 is of conventional construction and is adapted to rotate the shaft 27 and its sprocket in a clockwise direction (Fig. 5) when swung in such direction so as to advance 20 the upper flight of the chain conveyor 23 toward the machine 15; however, the lever is freely rotatable relative to the shaft in a counterclockwise direction (Fig. 5) whereby no rotation is imparted to said shaft when said lever is swung in 30 such direction.

An elongated link 46 pivotally connects the ratchet lever to one end of a lever 47 which is pivotally supported by a suitable clevis bracket 48 (Fig. 4). The pivoted lever 47 extends forwardly beneath the table and has a foot pedal 49 pivotally fastened to its forward end. An opening 50 is formed in one of the planks of the usual platform 51 for guiding the foot pedal 49, said platform extending longitudinally of the table and immediately forwardly thereof and of the machine 15 for supporting one or more operators. By depressing the foot pedal, the lever 47 is pivoted in a counter-clockwise direction (Fig. 4) so as to force the link 46 upwardly and thereby 45 swing the ratchet lever in the same direction. In this manner, the shaft 27 and sprocket 25 are rotated in a counter-clockwise direction (Fig. 1) to advance the chain conveyor 23 toward the machine 15. It is pointed out that the ratchet lever 50 and other elements are arranged so as to impart a predetermined travel to the conveyor upon each actuation of said lever for positioning the work in the desired relation to the dies 19 and 20 of the machine 15. Ordinarily, the weight of the link is sufficient to return the elements to their 55 inoperative position shown in Figs. 1, 4 and 5.

For maintaining the work in engagement with the endless chain, hold-down members 52 are pivotally mounted on the table and each member includes an angular, overhanging guard rail or bar 53 overlying and in longitudinal alignment with the upper flight of said chain. A plurality of transverse arms or straps 54 connect each bar 53 to a longitudinal shaft 55 which has its ends 65 journaled in suitable collars 56 carried by the intermediate portions of the cross bars 14. Thus, each member 53 is pivotally supported above the table and is adapted to be swung downwardly relative thereto so as to dispose its bar 53 into 70 an overlying relation to the chain conveyor. Downward movement of the member is limited by stop lugs 57 carried by and projecting upwardly from the forward side rail 12 for engagement with the straps 54 (Figs. 3 and 4). In order to maintain 75

the louvers L and end brackets B in fixed relation during their advancement by the conveyor, the bar 53 of each member preferably has its flanges directed forwardly and downwardly in overlying and overhanging relation to the upper flight of said conveyor. As shown in Figs. 1 and 2, the left-hand table that receives the finished work from the machine is provided with one or more hold-down members 52 and, if desired, may be of a construction identical to the right-hand table and include a similar conveyor (not shown).

From the foregoing, it is believed to be readily apparent that work, such as the louvers L and end brackets B, may be held in a fixed position while fed semi-automatically to the machine 15 by the chain conveyor 23. The individual pivotal mounting of the hold-down members 52 permits upward swinging of the same for positioning of work upon the conveyor. As soon as the first end bracket passes beyond the right-hand member, a second bracket and louvers may be placed upon the conveyor upon upward swinging of said right-hand member. The hold-down member of the left-hand table assists in maintaining the work against movement during operation of the machine and is particularly effective when said work passes from beneath the left-hand, hold-down member of the right-hand table.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A work feeding and positioning mechanism including, a support, an endless conveyor carried by the support, hold-down means pivotally connected to said support and having an angular member overlying and extending longitudinally of the conveyor for holding angular work in engagement with said conveyor, the hold-down means and its angular member being pivotal in a vertical arc transversely of said conveyor to permit positioning of the work, and drive means for said conveyor.

2. A work feeding and positioning mechanism including, a support, an endless chain conveyor carried by the support, a hold-down member having an angle bar overlying and extending longitudinally of the conveyor for holding angular work in engagement with said conveyor, the hold-down member being pivotally connected to said support for swinging movement in an arc transverse and about a horizontal axis parallel to said conveyor to permit positioning of the work, and drive means for intermittently actuating said conveyor.

EDEN T. KITCHELL.
